GOTTLIEB JAHN, OF KIEL, AND ARTHUR RUNKWITZ, OF ELMSCHEHNAGEN, NEAR KIEL, ASSIGNEES TO FRIED. KRUPP GERMANIAWERFT AKTIENGESELLSCHAFT, OF KIEL-GAARDEN, GERMANY.

STEAM BOILER HEATED BY THE WASTE GASES OF INTERNAL-COMBUSTION ENGINES.

Application filed October 8, 1924, Serial No. 742,457, and in Germany October 26, 1923.

The invention relates to steam boilers which are heated by the waste gases of internal combustion engines and has for its object to improve the thermal output of such gases.

On the drawing is illustrated, by way of example, a preferred embodiment of the subject-matter of the invention.

Fig. 1 showing a vertical section of the boiler,

Fig. 2 showing a section on line 2—2 of Fig. 1, seen from above,

Fig. 3 being a partial plan view of a partition plate used in the foundation of the boiler.

Referring to the drawing, A denotes the boiler which is formed by a vertical cylindrical fire tube boiler, B is the foundation on which the boiler A is supported and the cylindrical sheet-metal wall of which surrounds the heating chamber C and is lined with refractory bricks. The bottom plate a^1 of the boiler A is inwardly cambered to such an extent, that a high room is formed 20 the side wall of which is surrounded by the boiler water and which thus considerably increases the heating surface of chamber C. Fire tubes I lead from the chamber C to the chimney.

The waste gases are supplied from below and first enter an annular distributing chamber F into which fits the exhaust pipe of the internal combustion engine. The annular chamber F, in its turn, is connected to the heating chamber C by upwardly directed passages E which are outwardly and laterally inclined. To this end the refractory bottom layer of the heating chamber C is supported on a cast iron plate G which is composed of 30 four parts and has the shape illustrated in Fig. 3. This plate is provided with box-shaped inclined extensions g^1 each inculding one of said passages E. The latter fit into the heating chamber C near the outer wall thereof.

The gases entering the discharging chamber F come to a state of rest therein and then enter the heating chamber C through the passages E in a well-ordered flow.

The openings E extending obliquely through the base of the heating chamber

around its whole circumference impart to the gases passing through them a change in direction, the original motion being changed to a circulating, upwardly working motion direction toward the wall of the boiler. A great velocity is imparted to the streams of waste gas in this way, which is particularly desired in order to increase the exchange of heat between the gases and the walls of the chamber C. The strong circulating motion provides further that in their upwardly turning path the gases come in contact with all parts of the walls, and stationary separating layers of air between the walls and the hot gases, which would permit only a sluggish exchange of heat, do not arise. Upon rising in the chamber C, they will thus strike along the wall of the water chamber of the boiler and deliver to it the main portion of their heat. Then the gases pass through all of the fire tubes D and escape into the chimney after having delivered the remainder of their effective heat.

The described method of feeding the waste gases results in a high-grade utilization of their heat content.

A peep hole H permits of inspecting the heating chamber C from outside. J denotes an oil nozzle which may temporarily be started for additional heating in case the heat content of the waste gases should decrease and not suffice for heating the boiler.

Claim.

In a steam boiler to be heated by the waste gases of internal combustion engines and comprising a water chamber, a heating chamber projecting from below into said water chamber so as to form a water leg around said heating chamber, a plurality of fire tubes leading from said heating chamber through said water chamber; a collecting chamber for the waste gases arranged below said heating chamber, and passages in the wall existing between said two chambers arranged both in an outwardly and laterally inclined direction.

The foregoing specification signed at Hamburg, Germany, this 18th day of September, 1924.

GOTTLIEB JAHN.
ARTHUR RUNKWITZ.
